UNITED STATES PATENT OFFICE

2,167,498

ELECTRIC VALVE CIRCUIT

Dudley E. Chambers, Scotia, N. Y., assignor to
 General Electric Company, a corporation of
 New York

Application March 29, 1938, Serial No. 198,656

6 Claims. (Cl. 250—27)

My invention relates to electric valve circuits and more particularly to control circuits for electric valve means of the type employing ironizable mediums such as gases or vapors.

5 More specifically, my invention relates to improvements in circuits of the nature disclosed and claimed in United States Letters Patent No. 2,104,633, granted January 4, 1938, upon an application of E. F. W. Alexanderson, and which 10 is assigned to the assignee of the present application.

In electric valve circuits which employ a plurality of individual arc discharge paths, it has been found that the continuous rating of the 15 electric valve group may be increased by utilizing the substantially greater short-time or momentary current ratings of the individual arc discharge paths. Particularly in connection with electric valve means of the type employing mercury pool 20 cathodes and immersion-ignitor control members, it has become apparent that it is highly desirable to utilize the larger short-time or momentary current ratings of the individual arc discharge 25 paths by causing the paths to conduct current in a predetermined order or in a predetermined sequence. By the term "immersion-ignitor 30 control member" is meant that type of control member which has an extremity thereof immersed below the surface of the mercury pool cathode and 35 which is of a material having a specific electrical resistivity substantially greater than that of the associated mercury pool cathode. It has been found that an immersion-ignitor or make-alive type control members may be constructed of a 40 material such as boron-carbide or silicon-carbide, or of a material such as that disclosed and claimed in United States Letters Patent No. 1,822,742, granted September 8, 1931, on an application of Karl B. McEachron and assigned 45 to the assignee of the present application.

Where a number of electric valves are connected in parallel relation to conduct current in the same direction and where it is desirable to increase the continuous current rating of the electric 50 valve group by causing the valves to conduct current in a predetermined order, it has been found important to employ controlling means which assure that one of the control members of the electric valves is always connected to the source which energizes the control members.

It is an object of my invention to provide a new and improved electric valve circuit.

It is another object of my invention to provide a new and improved excitation system for electric 55 valve apparatus.

It is a further object of my invention to provide a new and improved arrangement for increasing the continuous rating of electric valve means which employ mercury pool cathodes and associated immersion-ignitor type control members. 5

In accordance with the illustrated embodiment of my invention, I provide an improved electric valve circuit for energizing a load circuit, such as a welding circuit, from an alternating current supply circuit through electric valve apparatus of the type employing an ironizable medium and which includes two pairs of parallel-connected arc discharge paths, the respective pairs of arc discharge paths being oppositely connected relative to each other but the individual discharge paths of each pair being connected to conduct current in the same direction. The continuous current rating of the respective valve groups is substantially increased by causing the arc discharge paths to conduct current alternately to utilize the substantially greater short-time or momentary current ratings of the valves. The immersion-ignitor control members are energized from an excitation circuit which is energized in accordance with the anode-cathode voltage of 25 the discharge paths and includes an electric valve of the controlled type which effects energization of the control members in accordance with a periodic control voltage which is generated by a separate timing circuit. In order to assure 30 that one of the immersion-ignitor control members is always connected to the excitation circuit, I provide an improved switching device which includes pairs of overlapping contacts having 35 periods of simultaneous closure. The switching device is provided with an actuating coil which is periodically energized to effect alternate energization of the control members of the electric valves in each group to cause the respective arc discharge paths to conduct current alternately. 40 A pair of relays is employed to effect the periodic energization of the actuating coil of the switching device, one of the relays controlling the energization of the actuating coil and the other relay being responsive to the operation of the first relay to effect periodic operation thereof. 45

For a better understanding of my invention, reference may be had to the following description taken in connection with the accompanying drawing, and its scope will be pointed out in the appended claims. The single figure of the accompanying drawing diagrammatically illustrates an embodiment of my invention as applied to an electric valve system for energizing a welding circuit. 50 55

Referring now to the single figure of the drawing, my invention is diagrammatically illustrated as applied to an electric valve translating circuit for energizing a load circuit 1, such as a welding circuit, from an alternating current supply circuit 2. Energy is transmitted to the welding circuit 1 through a transformer 3 and through two groups 4 and 5 of electric valves. If desired, a suitable circuit controlling means, such as a switch 6, may be interposed between the supply circuit 1 and the translating apparatus. The groups of electric valves 4 and 5 are reversely connected in parallel so that these groups are capable of transmitting alternating current to the welding circuit 1. Each group 4 and 5 includes a plurality, such as a pair, of electric valve means 7 and 8. Electric valve means 7 and 8 are preferably of the type employing an ionizable medium, such as a gas or a vapor, and each includes an arc discharge path comprising an anode 9, a cathode 10 which may be of the self-reconstructing type such as a mercury pool cathode, and an immersion-ignitor control member 11 having an extremity thereof extending below the surface of the associated mercury pool cathode. The electric valves 7 and 8 in groups 4 and 5 are connected to conduct current in the same direction, and have corresponding electrodes connected across the same points of potential difference in the electric translating circuit.

I provide excitation circuits 12 and 13 which are associated with the groups 4 and 5 of the electric valves, respectively, to effect energization of the respective associated control members 11. The excitation circuits 12 and 13 are connected to be energized in accordance with the respective anode-cathode voltages of the groups of valves and each includes an electric valve 14 which is preferably of the type employing an ionizing medium, such as a gas or a vapor, and each includes an anode 15, a cathode 16 and a control member or grid 17. A suitable current responsive and protective means, such as a fuse 18 and a current limiting resistance 19, may be connected in series relation with each of the electric valves 14. In order to obtain a negative unidirectional biasing potential to maintain the control electric valves 14 nonconductive except during those intervals when it is desired to energize the associated control members 11 of electric valves 7 and 8, I employ any suitable means such as rectifiers 20, which may be energized from the alternating current circuit 2 and may include a transformer 21 and a pair of unidirectional conducting devices such as electric valves 22. The rectifier 20 associated with each excitation circuit establishes a negative unidirectional voltage across a suitable circuit, such as a parallel connected resistance 23 and a capacitance 24. A capacitance 25 may be connected across the cathode 16 and grid 17 of the control electric valve 14 in each of the excitation circuits to absorb transient voltages which may be present in the circuits. As a means for introducing into the excitation circuit 12 a periodic voltage or an impulse of voltage to render the associated control valve 14 conductive at the desired time and during predetermined intervals, I provide a resistance 26 which is energized by a timing circuit described hereinafter.

In the arrangement shown in the figure, the electric valves 7 and 8 of group 5 are shown as being arranged to follow the electric valves 7 and 8 of group 4. This is accomplished by employing excitation circuit 13 which is responsive to

the energization of the load circuit 1 by means of the electric valves 7 and 8 of group 4. When the load circuit 1 is energized, control electric valve 14 of excitation circuit 13 is rendered conductive by a voltage appearing across a capacitance 13' which is connected in series relation with the control member of this valve. The capacitance 13' is energized in response to the energization of the transformer 3 by means of a transformer 13'' which is connected across the primary winding of transformer 3. Certain features of this type of control, involving leading and trailing electric valves, are disclosed and claimed in United States Reissue Patent No. 20,335, granted April 20, 1937, on an application 15 of Harold W. Lord and which is assigned to the assignee of the present application.

As an agency for producing a periodic voltage for effecting periodic energization of the load circuit 1, as for example in line or seam welding operations, I employ a timing circuit 27. The timing circuit 27 transmits impulses of current through resistance 26 in excitation circuit 12 to render the control electric valve 14 conductive periodically and hence render the electric valves 7 and 8 in groups 4 and 5 conductive during corresponding intervals. The timing circuit 27 includes a source of unidirectional voltage comprising conductors 28 and 29. The source of unidirectional voltage may be produced by a suitable means, such as a full wave rectifier 30, including a transformer 31 and a pair of unidirectional conducting devices 32. A voltage divider comprising a resistance 33, which is connected across conductors 28 and 29, is arranged to have adjustable contacts 34 and 35. Capacitance 36 is connected to be energized from the direct current circuit, including conductors 28 and 29, through an adjustable resistance 37. A periodic timing quantity, such as a periodic voltage, is generated by periodically discharging the capacitance 36 through an electric valve 38. Electric valve 38 is preferably of the type employing an ionizable medium and comprises a control member 39. In order to render the electric valve 38 nonconductive after each discharge of capacitance 36, I connect an inductance 40 in series relation therewith. As an agency for effecting the proper and desired synchronization between the voltage of the alternating current circuit 2 and the time at which the periodic voltage impulses occur, I employ a transformer 41 having a primary winding 42 and a secondary winding 43. Primary winding 42 is connected to the alternating current circuit 2 through any suitable phase shifting device such as a rotary phase shifter 44. By adjustment of the rotary phase shifter 44, it is possible to control the phase relation between the voltage of the alternating current circuit 2 and the time of initiation of the various impulses of the periodic voltage. Secondary winding 43 is connected between the adjustable contact 34 of the voltage divider and the control member 39 of electric valve 38. Where it is desired to obtain a periodic timing quantity, such as periodic voltage which is of pronounced peaked wave form, such as in those applications where it is desired to maintain a high ratio of the period of nonconduction to the period of conduction of the electric valves, I employ a serially connected resistance 45 and a capacitance 46 which is connected to be energized in accordance with the voltage appearing across the terminals of resistance 37. This circuit is disclosed and claimed in United States Letters Patent No. 2,098,052, 75

granted November 2, 1937, on an application of Harold W. Lord, and which is assigned to the assignee of the present application.

To effect energization of the control members 11 of electric valves 7 and 8 in groups 4 and 5 in a predetermined order, I provide a switching device 47. The switching device 47 comprises an armature member 48, a core member 49, an associated actuating coil 50, and two groups of contactor mechanisms 51 and 52. The contactor mechanisms 51 and 52 are similar in construction and arrangement and are associated with groups of valves 4 and 5, respectively. The contactor mechanism 51 includes stationary contacts 52 which are associated with electric valve 7 in group 4 and stationary contacts 54 which are associated with electric valve 8 in group 4. Movable contacts 55 and 56 are mounted on the armature member 48 and are arranged to be in overlapping relation with the contacts 53 and 54, that is, are arranged to have periods of simultaneous closure therewith during the reciprocating action of member 48. This overlapping action may be obtained by any suitable arrangement and is diagrammatically illustrated as being accomplished by the utilization of a spring 57 which tends to maintain the movable contacts 55 and 56 in spaced relation. A collar 58, which is mounted on the member 48, moves the contact 56 out of engagement with the stationary contacts 54 when the movable member 48 is in the upper position, that is, when the actuating coil 50 is energized. When the member 48 is in the lower position, that is, in the deenergized position, the contactor mechanism attains the position shown in the drawing. Contactor mechanism 52 includes stationary contacts 59 and 60 which are associated with electric valves 7 and 8, respectively, in group 5, and movable contacts 61 and 62 are associated with stationary contacts 59 and 60, respectively.

To obtain periodic energization of the actuating coil 50 of the switching device 47 so that the member 48 reciprocates to effect alternate energization of the control members 11 of electric valves 7 and 8 in groups 4 and 5, I provide a circuit 63 which may comprise a pair of relays 64 and 65. Relay 64 periodically energizes actuating coil 50 of the switching device 47 from a source of current 66. Where the source of current is alternating and where it is desired to energize the coil 50 with direct current, a suitable rectifying arrangement, such as a full wave rectifier 67, may be interposed between the source 66 and the coil 50. Relay 65, which is energized in response to the operation of relay 64, effects de-energization of the relay 64 when relay 64 is in the energized position so that a pumping action is obtained between relays 64 and 65. Relay 64 comprises an armature 68, an actuating coil 69, pairs of stationary contacts 70 and 71, and a movable contact member 72. When the relay 64 is in the deenergized position, that is, in the lower position, coil 50 of the switching device 47 is energized, and when the member 68 of relay 64 is in the energized or upper position, the coil 50 is deenergized and relay 65 is energized. A suitable rectifying device 73 may be interposed between the source 66 and the actuating coil 69 of relay 64, if desired. Relay 65 includes movable contact 74 and stationary contacts 75 and an actuating coil 76 which is energized by the relay 64 from the source 66 when the relay 64 is in the energized position. A rectifier 77 may also be used in connection with relay 65, if desired, and

current limiting resistances 78 and 79 may be connected in the relay circuits to obtain the desired value of control currents. It is to be noted that relays 64 and 65 are interlocked to provide intermittent or periodic energization of the actuating coil 50 of the switching device 47.

The operation of the embodiment of my invention shown in the single figure of the drawing will be explained by considering the system when it is operating to effect periodic energization of the load circuit 1. As is well understood by those skilled in the art, the electric valves in the groups 4 and 5 conduct current to transmit alternating current to the load circuit 1 in the event the periodic voltage produced by the timing circuit 15 27 is of sufficient period. The excitation circuits 12 and 13, which are energized in accordance with the anode-cathode voltages of the respective groups of valves, transmit current to the immersion-ignitor control members 11 when the timing circuit 27 dictates such energization. During the intervals when the timing circuit 27 dictates energization of the control members 11, the control electric valve 14 of excitation circuit 12 is rendered conductive by the positive voltage appearing across the terminals of the resistance 28 in excitation circuit 12, and electric valve 14 conducts current to the immersion-ignitor control member 11 until arc discharges are initiated in the associated valves. As soon as arc discharges are initiated, the current through the immersion-ignitor control members decreases to substantially a zero value by virtue of the lower resistance of the main discharge paths of the electric valves. This action will be understood 35 when it is considered that the anode-cathode voltage decays substantially as soon as electric valve 7 or 8 is rendered conductive.

Electric valves 7 and 8 of group 5 follow the electric valves 7 and 8 of group 4. That is, the former electric valves are rendered conductive only after the electric valves in group 4 effect energization of the load circuit 1. The voltage appearing across the terminals of the primary winding of transformer 3 energize transformer 45 13" to introduce into excitation circuit 13 a voltage sufficient in magnitude to overcome the effect of the negative biasing potential, so that the control electric valve 14 in excitation circuit 13 effects energization of the immersion-ignitor control member 11 of either valve 7 or 8 in group 5, depending upon the position of the movable element 48 of the switching device 47.

The manner in which the timing circuit 27 generates the periodic voltage is well understood 55 by those skilled in the art. Briefly described, the periodic voltage is generated by the periodic charging and discharging of the capacitance 38. For a more detailed explanation of the operation of this circuit, reference may be had to the above 60 second mentioned patent of Harold W. Lord.

Switching device 47 alternately energizes control members 11 of electric valves 7 and 8 in groups 4 and 5, so that electric valves 7 and 8 conduct current alternately to increase the continuous rating of the valve group by utilizing the substantially greater short-time or momentary ratings of these valves. Actuating coil 50 is periodically energized by means of the relays 64 70 and 65 so that the member 48 of device 47 attains a reciprocating action. Due to the fact that the movable contacts 55 and 56 are arranged to have an overlapping action with respect to the associated stationary contacts 53 and 54, respec- 75

tively, the excitation circuits 12 and 13 will always be connected to at least one of the control chambers 11.

The position of the movable members of the switching device 47 and relays 64 and 65 shown in the drawing is that which is attained when the system is deenergized. As soon as switch 6 is moved to the closed circuit position, coil 69 of relay 64 is energized, raising movable contact 72 to disengage stationary contacts 70 and to engage stationary contacts 71. By such action, coil 50 is maintained deenergized and coil 76 of relay 65 is energized. As soon as coil 76 of relay 65 is energized, movable contact 74 thereof disengages contacts 75, effecting deenergization of actuating coil 69 or relay 64. Upon such deenergization, movable contact 72 will engage stationary contacts 70, effecting energization of the actuating coil 50 of the switching device 47 and moving the member 48 to the upper position. A pumping or interlocking action is maintained between relays 64 and 65 so that the actuating coil 50 is periodically energized. In this manner the control members 11 of electric valves 7 and 8 in groups 4 and 5 are alternately energized to cause the electric valves 7 and 8 to conduct current alternately. Furthermore, due to the periods of simultaneous closure of the contactor mechanisms of this device, at least one of the control members of the valves in each group is always connected to the associated excitation circuit.

While I have shown and described my invention as applied to a particular system of connections and as embodying various devices diagrammatically shown, it will be obvious to those skilled in the art that changes and modifications may be made without departing from my invention, and I, therefore, aim in the appended claims to cover all such changes and modifications as fall within the true spirit and scope of my invention.

What I claim as new and desire to secure by Letters Patent of the United States is:

1. In combination, a supply circuit, a load circuit, an electric translating circuit interconnecting said circuits and including electric valve means having a plurality of discharge paths connected in parallel relation across the same points of potential difference in said translating circuit and being connected to conduct current in the same direction, said electric valve means each being provided with a control member for initiating discharges in the associated discharge path, means for generating a voltage to energize the control members, and means for energizing the control members in a predetermined order to cause said discharge paths to conduct current in said order and including switching means having overlapping contacts to assure that one of the control members is always connected to said first mentioned means.

2. In combination, a supply circuit, a load circuit, an electric translating circuit interconnecting said circuits and including electric valve means having a plurality of discharge paths connected in parallel relation across the same points of potential difference in said translating circuit and being connected to conduct current in the same direction, said electric valve means each being provided with a control member for initiating discharges in the associated discharge path, a source of current, switching means having overlapping contacts to assure that one of said control members is always connected to said source, said switching means including an actuating coil, and means for periodically energizing and de-

energizing said coil to energize the control members in a predetermined order so that the discharge paths conduct current in said order comprising a relay for periodically energizing said coil and a second relay responsive to the operation of the first mentioned relay for effecting periodic operation of said first mentioned relay.

3. In combination, a supply circuit, a load circuit, an electric translating circuit interconnecting said circuits and including electric valve means having a plurality of discharge paths connected in parallel relation across the same points of potential difference in said translating circuit and being connected to conduct current in the same direction, said electric valve means each being provided with a control member for initiating discharges in the associated discharge path, a source of current, a switching device for connecting said source to the control members and including sets of contacts having periods of simultaneous closure to assure that one of the control members is always connected to said source, said switching device including an actuating coil, and means for periodically energizing and deenergizing said coil to energize the control members in a predetermined order so that the discharge paths conduct current in the same order and comprising a pair of interlocked relays for effecting periodic energization of said coil.

4. In combination, a supply circuit, a load circuit, an electric translating circuit interconnecting said circuits and including electric valve means having a pair of discharge paths connected in parallel relation across the same points of potential difference in said translating circuit and being connected to conduct current in the same direction, said electric discharge means each being provided with a control member for initiating discharges in the associated discharge paths, a source of current, a switching device for connecting said source to the control members and including two sets of overlapping contacts having periods of simultaneous closure to assure that one of the control members is always connected to said source, said switching device including an actuating coil, and means for periodically energizing said coil to effect alternate energization of the control members including a relay for periodically energizing and deenergizing said coil and a second relay controlled by the first mentioned relay for effecting periodic operation thereof.

5. In combination, an alternating current circuit, a load circuit, an electric translating circuit interconnecting said circuits and including electric valve means having a pair of discharge paths connected in parallel relation across the same points of potential difference in said translating circuit and being connected to conduct current in the same direction, each of said discharge paths being provided with an anode, a cathode and an immersion-ignitor control member, an excitation circuit connected to be energized in accordance with the anode-cathode voltage of said discharge paths, a switching device including two sets of overlapping contacts having periods of simultaneous closure to assure that one of the control members is always connected to said excitation circuit, said switching device including an actuating coil, and means for periodically energizing said coil to effect alternate energization of the control members so that said discharge paths conduct current alternately.

6. In combination, an alternating current supply circuit, a load circuit, an electric translating circuit interconnecting said circuits and including

5 electric valve means having a pair of discharge paths connected in parallel relation across the same points of potential difference in said translating circuit and being connected to conduct current in the same direction, each of said discharge paths being provided with an anode, a cathode and an immersion-ignitor control member, an excitation circuit connected to be energized in accordance with the anode-cathode voltage of said discharge paths and comprising an electric valve of the controlled type, a switching

device including two sets of overlapping contacts having periods of simultaneous closure to assure that one of the control members is always connected to said controlled electric valve, said switching device including an actuating coil, and means for periodically energizing said coil to effect alternate energization of the control members so that said discharge paths conduct current alternately.
